UNITED STATES PATENT OFFICE.

JOHN ADAM WENTZ, OF CRAFTON, PENNSYLVANIA.

DEVICE FOR OPENING AND CLOSING CHAIN LINKS.

Application filed July 23, 1926. Serial No. 124,404.

This invention relates to a machine for opening and closing the terminal links of the cross chain of conventional automobile skid chains, whereby a defective cross chain may be removed from associated parallel side chains and readily replaced by a new one in a simple and expeditious manner.

The primary object of the invention is to provide a simplified and improved chain link opening and closing device of the type set forth in the U. S. patent granted March 14, 1922, to John McLachlan, No. 1,409,876, whereby expensive special construction of the frame of the device or machine for providing for holding the links to be opened or closed, and the use of an anvil, is rendered unnecessary.

Primarily, the invention aims to provide the tapered blade member of the plunger with a flat upper surface so that said blade member acts as an effective support for the chain links when being closed by the plunger head, and to provide further for most effective opening of the chain links when supported in position to be entered by the blade member.

Other objects will become apparent as the nature of the invention is better understood, and the same consists in the novel form, combination and arrangement of parts herein-after more fully described, shown in the accompanying drawing and claimed.

In the drawing, wherein like reference characters indicate corresponding parts throughout the several views,

Figure 1 illustrates in perspective one embodiment of the invention;

Figures 2 and 3 are broken perspective views of the device respectively illustrating the use of the device in disengaging and re-placing a terminal link of the cross chain; and

Figure 4 is a top plan view, partly broken away, showing a modified form of the plunger which may be used in lieu of the plunger shown in Figure 1.

Referring more in detail to the drawing, 5 indicates a support upon which is mounted a frame 6 which is secured to said support in any suitable manner, as by means of base flanges 7 bolted thereto. The frame 6 is provided at one end portion with a pair of spaced upstanding transverse ribs or posts 8 which are vertically slotted or bifurcated to form a guideway in which slides a plunger 9, the plunger 9 being retained in the guideway by means of a detachable cover plate 10 connecting the ribs or posts 8 and having its ends se-

cured upon the upper ends of said ribs or posts 8 so as to close the upper ends of the slots of the latter whereby upward displacement of the plunger 9 is prevented.

The plunger 9 comprises a head 11 formed by tapering the sides of a portion of the forward ends of the plunger, and a wedge-shaped blade 12 directly below and projecting forwardly beyond the head 11.

The frame 6 is provided at one end with a yoke 13 in which a lever 14 is pivoted or fulcrumed, and the upper end of this lever 14 is connected to the adjacent end of the plunger 9 by means of links 15. Any suitable means may be operatively connected to the lower end of lever 14 for facilitating its actuation to reciprocate the plunger 9, such as a treadle or the like as illustrated in the McLachlan patent mentioned above.

An integral tail-stock 16 is formed at the other end of the frame 6 and braced at its outer side by vertical webs 17, an aperture 18 being formed in the tail-stock for reception of the ends of blade 12 when it is in its operated position. The inner side of the tail-stock may be provided with a detachable or permanent steel base plate 19 having an aperture similar to and registering with the aperture 18 of the tail-stock and adapted to receive the impacts of the plunger.

It will be noted that the blade portion 12 is tapered at the bottom and side, but has a perfectly flat upper surface as at 20 to provide a seat upon which may be placed the terminal links of a new chain in the operation of replacement. This construction of the blade portion will also tend to offset any tendency of the terminal link of a defective cross chain from unduly swinging or moving when the blade portion 12 enters the same in removing said defective cross chain from the parallel side chains of the automobile skid chain. By this particular formation of the blade portions 12 a special formation of the frame 6 to provide depression and seat portions for holding the terminal link, is rendered unnecessary, and the necessity for the use of an anvil is avoided.

The plunger 9 may be formed with a 105 projecting lug 21 directly above the head 11 and overlying the inner portion of the blade portion 12 so as to contact with the base plate 19 and limit the movement of the plunger when projected to a position wherein the terminal link is completely closed, and at the same time guard against shearing of the

links. Further, the head 11 is preferably tapered to a knife edge so that it will slightly bite into the links and prevent its lateral displacement from the upper surface 20 of the blade portion 12 when being closed. In view of this preferable knife edge formation of the head 11, the use of the stop lug 21 is preferable, although said lug 21 may be omitted as illustrated in Figure 4. Otherwise the 10 construction of plunger in Figure 4 is identical with that of the other figures.

When it is desired to remove a defective cross chain from its associated side chains, one of the terminating links 22 of said cross 15 chain is placed against the base plate 19 or on the end of the blade member 12 in a manner generally illustrated in Figure 2. The lever 14 is then actuated to slide the plunger 9 toward the tail-stock and cause the blade 12 to pass into the link and the openings of the tail-stock and its base plate. In this way the link is sufficiently spread for being disengaged from the associated link of the side chain. The plunger is then retracted so as 20 to withdraw the blade portion 12 from the link whereby the latter may be more readily freed from the parallel side chains.

The open terminal links of a new cross chain are then engaged with the parallel side 30 chains of the skid chain, and each terminal link of the new cross chain is closed and fastened in the following manner:

As shown in Figure 3 the open terminal link of the new cross chain is disposed to 35 slightly rest upon the upper surface 20 of

the blade portion 12, whereupon the plunger 9 is projected for forcing the terminal link against the base plate 19 of the tail-stock and at the same time applying pressure to the opposite side of the link by engagement 40 of the head 11 therewith. In this way the link is effectively closed and secured to the associated side chain without the use of an anvil.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

In a device of the character described, a frame comprising a base having a guideway 55 and spaced therefrom a tail piece having an opening therein, a plunger reciprocating in said guideway, and comprising a head portion and a blade portion, the upper surface of said plunger blade being flat and horizontal 60 and its sides and bottom part tapering, the base in the space between the tail piece and the guide portion of the device being flat and uninterrupted so that the link may be placed on said base during the opening thereof, and 65 the sides of the closing portion of the tail piece being tapered.

In testimony whereof I affix my signature.

JOHN ADAM WENTZ.
